UNITED STATES PATENT OFFICE.

JOSEPH J. WALSER, OF CHICAGO, ILLINOIS, ASSIGNOR TO THE GOSS PRINTING PRESS COMPANY, OF CHICAGO, ILLINOIS, A CORPORATION OF ILLINOIS.

VARIABLE-SPEED DRIVING MECHANISM.

967,470.

Specification of Letters Patent. Patented Aug. 16, 1910.

Application filed October 11, 1909. Serial No. 522,128.

To all whom it may concern:

Be it known that I, JOSEPH J. WALSER, a citizen of the United States, residing at Chicago, in the county of Cook and State 5 of Illinois, have invented certain new and useful Improvements in Variable-Speed Driving Mechanism, of which the following is a specification, reference being had to the accompanying drawings.

10 My invention relates to variable speed driving mechanism adapted to be driven by an electric motor, and it is particularly adapted to variable speed driving mechanism for printing presses, by means of which the 15 press may be driven at a slow speed and at a higher speed and by means of which the speed of the press may be changed while the press is running from slow speed to high speed.

20 More particularly, my invention relates to improvements in variable speed driving mechanism of the general character shown in application for Letters Patent of the United States to me, Serial No. 466,121, 25 filed December 5, 1908. In these mechanisms referred to, speaking generally, the main driving shaft by which the press or other machine was driven, was adapted to be driven by a motor running at a constant speed, and variable speed driving 30 mechanism was connected with that driving shaft by which the press might be driven at either a slow speed or a high speed while the main driving shaft was constantly driven at the same speed and without stopping the press, and the apparatus 35 was especially adapted to that end.

In my present invention, the variable speed driving mechanism is adapted to be 40 driven by an electric motor whose speed may be varied, and it is the object of my invention to provide a driving mechanism which may be shifted from the low speed to the high speed while the press is in motion 45 and in which at the same time that the shift is made the speed of the motor may be also varied and shifted gradually from low speed to high speed as the change between low speed and high speed in the 50 driving mechanism is made. By means of this mechanism, I can obtain a much greater variation in speed and a more gradual shift from the slow speed to the high speed of the ultimately driven mechanism, such as a 55 printing press. I accomplish this object by

the means shown in the drawings and hereinafter specifically described.

That which I believe to be new will be pointed out in the claims.

In the drawings:—Figure 1 is a top or 60 plan view with one of the bed frames of the press partly broken away to expose the parts below. Fig. 2 is an end elevation, showing in dotted lines a part of the press frame and press driving gears. Fig. 3 is a 65 section on line 3—3 of Fig. 2. Fig. 4 is a detail, being a section on line 4—4 of Fig. 1. Fig. 5 is a detail, being a section on line 5—5 of Fig. 3. Fig. 6 is a detail, being a section on line 6—6 of Fig. 3. Fig. 7 is an 70 enlarged detail, being a section on line 7—7 of Fig. 1. Fig. 8 is an enlarged detail, being a section on line 8—8 of Fig. 4. Fig. 9 is an enlarged detail, being a section on line 9—9 of Fig. 1. Fig. 10 is an enlarged detail, 75 being a section on line 10—10 of Fig. 9. Fig. 10^a is a detail, being a view of the stop mechanism by which the devices for changing the speed of the motor may be locked at low speed.

80 Referring to the drawings:—11 indicates the frame for the driving mechanism, and 12 indicates the bed plates of a press to which the driving mechanism is applied.

13 (shown in dotted lines in Fig. 2) indicates part of the side frame of the press on which are mounted driving gears 14—15—16—17,—all shown in dotted lines,—the gear 17 meshing with driving gear 15 and with a gear 18,—also in dotted lines,—90 which meshes with the driving gear on the driving mechanism hereinafter described.

19 indicates the main driving shaft, which is journaled in the frame 11 and is provided upon its outer end with a gear 20 which is 95 driven by means of a motor A conventionally illustrated in Fig. 3.

21 indicates a gear which is keyed upon the driving shaft 19.

22 indicates a spider which is revolvably 100 mounted upon the shaft 19 adjacent to the gear 21 and is provided with a flange rim 23.

24 indicates a flexible brake band upon which is mounted a brake shoe 25, which, 105 engaging the flange 23 of the spider 22, is adapted to hold the same against rotation when applied in the manner hereinafter described.

26—27 indicate small-sized gears which 110

are revolvably mounted on suitable studs on the arms of the spider 22 and mesh with the gear 21.

28—29 indicate gears which are keyed or otherwise secured to stub-shafts 30 which are journaled in the arms of the spider 22 and mesh respectively with the gears 26—27.

31—32 indicate gears of smaller diameter than the gears 28—29 and keyed or otherwise secured to the other ends of the stub-shafts 30.

33 indicates a disk which is revolvably mounted upon the shaft 19 adjacent to the spider 22, and carries secured thereto by any appropriate means, as by bolts 34, a gear ring 35, which meshes with the gears 31—32.

36 indicates a ratchet wheel which is keyed or otherwise secured to the hub of the disk 33.

20 37 indicates a pawl disk which is keyed or otherwise secured upon a sleeve 38 which is revolvably mounted upon the shaft 19. The pawl disk 37 is provided with pawls 39 which are adapted to be engaged by the ratchet wheel 36 so that when the shaft and ratchet are rotated in the direction indicated by the arrow on Fig. 5 the sleeve 38 will be carried around with it.

40 indicates a gear which is keyed or otherwise secured to the sleeve 38, and, meshing with the gear 18, through the medium of the gears 17—14—15—16, operates to drive the press.

41 indicates a drum which forms one member of a clutch mechanism which is preferably formed integral with the sleeve 38.

42 indicates a flexible brake band to which is secured a brake shoe 43 which is adapted when thrown on in the manner hereinafter described to brake the drum 41 and stop the mechanism.

44 indicates a collar which, pinned to the shaft 19, bears upon the interior surface of the drum 41 and operates to hold the parts in position.

45 indicates a clutch member which is provided with a hub 46 and is feathered upon the shaft 19 so as to slide longitudinally thereof. The inner surface of the rim of the clutch drum 41 and the outer periphery of the clutch 45 are correspondingly beveled and the clutch member 45 is provided with a clutch band 47 which is adapted, when the clutch 45 is slid into engagement with the clutch drum 41, to engage the inner surface of the rim thereof and cause the clutch drum 41 to be driven by the rotation of the clutch member 45 on the shaft 19. The hub 46 is provided with a peripheral groove 48.

60 From the above description, it will be obvious that when the shaft 19 by means of the gear 20 is driven in the direction shown by arrows in Fig. 2, the gears 28—29 will be driven, through the intermediate gears 26—27, in the same direction,—that

is, in the direction indicated by arrows in the said figure,—and if the brake 25 is free from the rim of the spider 22 so as to permit it to rotate, the spider will be rotated in the same direction,—that is, in the direction indicated by arrow on Fig. 2,—the gears 31—32 traveling around on the interior gear ring 35, and the speed at which this revolution will occur will depend upon the relative size of the gear 21 and the interior gear ring 35. When, however, the brake is applied to the spider, in the manner hereinafter described, so as to hold it against rotation, the gears 28—29 will be merely rotated in their bearings, rotating in the same direction the gears 31—32 which are keyed to the same stub-shafts. This will cause the disk 33 to be rotated upon the shaft 19 and in the same direction, the speed of this rotation, however, being still further diminished by the difference in size between the gears 28—29 and the gears 31—32, thus driving the disk at a much slower speed than the shaft 19. The engagement of the ratchet wheel 36 with the pawls 39 will drive in the same direction and at the same speed the pawl disk 37, which, being keyed to the sleeve 38, will rotate the gear 40 in the same direction and at the same speed as the disk 33 and pawl disk 37, which, through the medium of the several driving gears 14 to 18, will drive the press at slow speed. Of course during this movement the clutch members will be thrown out of engagement in the manner hereinafter described. If now the clutch members are thrown into engagement by the inward movement of the hub 46, which engagement will be gradual and not sudden by reason of the beveled engaging surfaces of the clutch members, the clutch drum 41 will gradually, as the clutch members are thrown into complete and tight engagement, be rotated in the same direction as the shaft 19 and at the same speed as said shaft, rotating of course in the same direction the gear 40 and driving the press through the medium of the interposed gearing at high speed. Of course the pawl disk 37 will also be driven at the same speed. The brake 25 still being on during the engagement of the clutch members and the spider 22 being therefore held against rotation, the ratchet 36 will be driven at the slow speed above described, but the pawl 39 will slip over the ratchet teeth permitting the pawl-disk 37 and connected parts to be driven at the high speed.

It will be obvious from the above description that the high speed mechanism may thus be put into operative relation with the press before the slow speed is put out of operative relation therewith, thus preventing the running of the press by its mere momentum and consequent slowing down during the period of shifting from one speed to the other. If the brake 25 is then thrown

off, the spider 22 will be free to rotate and will take up a speed the same as the shaft 19 through the operation of the several gears connected therewith above described.

- 5 The relative sizes of the gears will of course be such as to secure the desired difference between the slow and the high speeds, and may be varied to suit the demands of the case, it being obvious that the greater 10 the difference between the gear 21 and the internal gear 34 and between the gears 28-29 and 31-32, the greater will be the difference between the relative speeds of the shaft 19 and the disk 33 and therefore between 15 the slow speed and the high speed of the same. When the clutch members are disengaged, the brake 25 also being disengaged, if the brake 43 is applied, in the manner hereinafter described, to the drum 41, 20 the movement of the driving mechanism will be braked and the press driven thereby stopped.

The various parts above described are thrown into and out of engagement by the 25 following mechanism.

49 indicates a rock shaft which is journaled in suitable bearings below the base frames 12.

50 indicates a ratchet wheel provided with 30 two sets of teeth 51-52, which is keyed or otherwise secured to the outer end of the rock shaft 49.

53 indicates a hand-lever which is provided at its upper end with the usual latch 35 54 which is adapted to engage an arc-bar 55 so as to be held therein in either of three positions,—that is to say, with the press silenced, with the press running at slow speed, and with the press running at full speed,—as indicated respectively in Fig. 2 by the word "Off" and by the letters "S" 40 and "F," the parts in the several figures being represented in the position in which they are when running at full speed.

45 56 indicates a pawl which is pivoted on the lever 53 above the ratchet wheel 50 and is adapted to engage the ratchet teeth 51. The pawl 56 is provided with an arm 56^a which is adapted to be engaged by the pin 50 57 mounted in one of the base plates 12 so that when the lever is swung past the slow speed notch the pawl 56 will be lifted out of engagement with the teeth 51.

58 indicates a pawl which is pivotally carried upon the lower arm of the lever 53 and is adapted to engage the ratchet teeth 52 of the ratchet wheel 50 when the lever is swung to the right toward the "off" position.

59 (see Figs. 4 and 9) indicates a sleeve 60 which is secured to the rock-shaft 49 and, is provided with a lug 60, which, as is best shown in said figures, is preferably integral therewith and slopes slightly downward therefrom when the shaft 49 is in normal position.

61 indicates an arm which is pivotally connected at its upper end with a suitable bracket, as 62, on the under side of the base plate 12, and swings downward therefrom. The arm 61 is provided with a catch 63. 70 which, when the arm 61 is free to swing to its lowest position and the rock shaft 49 is rocked as hereinafter described by raising the arm 61, is adapted to drop in behind and below the lug 60 and prevent the rock 75 shaft 49 from being rocked back into its normal position until the latch 63 is disengaged.

64 indicates a cam which is carried upon the lower end of the lever 53 and is adapted, 80 when the parts are swung into the position shown in the figures, to engage the lower end of the arm 61, and, throwing it outward, in the position best shown in Fig. 9, to free it from the lug 60, permit the rock shaft 49 85 to return to normal position.

65 indicates an arm which is keyed or otherwise secured to the rock shaft 49 and projects upward therefrom.

66 indicates a rod one end of which is pivotally connected with the arm 65 and the other end of which is slidably mounted in a lug 67 on the frame 12. 90

68 indicates a collar which is secured to the rod 66. 95

69 indicates a spiral spring which, mounted upon the rod 66 between the lug 67 and collar 68, tends to yieldingly hold the rock shaft 49 in normal position,—that is to say, the position indicated by the several figures 100 in which both brakes are off.

70 indicates a lever which is pivotally mounted in a suitable bracket 71 which depends from one of the frame bars 12 and is secured thereto. The lower end of the lever 105 70 is connected by a link 72 with the lower arm of the lever 53, and it carries upon its upper end a beveled segmental gear 73.

74 indicates a shaft which is journaled in suitable bearings in the bracket 71 and carries near its outer end a bevel gear 75 which meshes with the beveled segmental gear 73. When the lever 53 is rocked in either direction, the lever 70 will be correspondingly moved through the medium of the link 72, 110 115 and, through the medium of the beveled segmental gear 73 and gear 75, the shaft 74 will be given a partial rotation or be rocked in one direction or the other.

76 indicates a collar which is secured to the 120 lower end of the shaft 74 and is provided with an arm 77 extending outward therefrom.

78 indicates a slide rod which is slidably mounted in suitable bearings 79-80 secured 125 to the framework.

81 indicates a link which is pivotally connected at one end with the slide rod 78 and at the other end with the end of the arm 77, whereby, when the shaft 74 is rocked, as 130

above described, the slide rod 78 will be moved longitudinally of itself in its bearings.

82 indicates a collar pinned or otherwise adjustably secured to the slide rod 78.

83 indicates a collar which is pinned or otherwise adjustably secured on the slide rod 78.

84 indicates a collar which is slidingly mounted on the rod 78 between the collars 82 and 83.

85 indicates a spiral spring which is carried upon the slide rod 78 between the collars 83 and 84.

15 86 indicates a lever which at one end is provided with a fork 87 which embraces the rod 78 and is adapted to be engaged by collars 82 and 84 and at the other end with a fork 88 which embraces the hub 46 and engages the peripheral groove 48 therein. The lever 86 is pivotally mounted upon a suitable bracket, as 89, on the frame 11.

It will be obvious from the above description that when the slide rod 78 is moved 25 downward in Fig. 1 the collar 82 engaging the fork 87 will rock the lever in one direction and throw the clutch members out of engagement. When the slide rod is moved in the other direction, the spring-seated collar 84 will engage the fork 87, and, rocking the lever 86 in the other direction, will move the clutch members into engagement. It will also be evident that when the lever 53 is moved from right to left in Fig. 2 the 30 relation of the parts is such that the clutch members will be moved toward one another and ultimately into engagement, and when the lever is moved in the other direction the clutch members will be moved away from each other and out of engagement, the 35 pinned collars 82 and 83 and the spring-seated collar 84 being suitably spaced on said shaft to permit the engagement of the clutch members at the proper time,—that is to say, after the slow speed position of the 40 lever has been passed in its movement from right to left.

90 indicates a collar which is keyed or otherwise secured to the shaft 49 and carries an arm 91 preferably integral therewith. The arm 91 carries a spring-seated pawl 92, best shown in Figs. 1 and 2.

94 indicates a collar which is revolvably mounted on the rock-shaft 49 adjacent to 55 the collar 90, and is provided on its periphery with a lug 95 which is adapted to be engaged by the pawl 92 when the rock shaft is rotated clock-wise in Fig. 7 so as to rotate the collar 94 in the same direction. The 60 collar 94 is provided with an arm 96 which projects upward therefrom and is preferably formed integral therewith.

97 indicates a rod which is pivotally connected at one end with the arm 96 and is 65 adapted at its other end to slide freely in

and out of an opening 98 in part of the framework 12 (see Fig. 7).

99 indicates a collar which is pinned or otherwise adjustably secured to the rod 97.

100 indicates a spiral spring which is carried on the rod 97 and bears at one end upon the collar 99 and at the other end upon the frame 12. The spiral spring 100 tends to yieldingly hold the arm 96 and sleeve 94 in the position shown in Fig. 7 and return the 75 same to said position when said arm 96 is rocked to the right in Fig. 7.

101 indicates a link, one end of which is pivotally connected with the arm 96 on the collar 94. The other end of the link 101 is pivotally connected with an arm 102 which is secured to and preferably formed integral with a collar 103 secured to a shaft 104 which is rotatably mounted in suitable 80 bearings 105 on the frame 11.

The brake band 42, by means of a rod 106, is connected with a lug 107 upon the arm 102, and the other end of the brake band 42 is secured to a suitable collar 108 loosely mounted upon the shaft 104. When the 90 shaft 49 is rocked clock-wise in Fig. 7 by the swinging of the lever 53 to the right and consequent engagement of the pawl 58 with ratchet teeth 52 on disk 50, the collar 90 will be rocked with it, the pawl 92 engaging the lug 95, rocking the arm 96 against the action of the spring 100 and tightening the brake band 42 so as to brake the mechanism. When the shaft 49 is rocked in the other direction so that the pawl 92 is freed from the lug 95, the 95 spring 100 will immediately rock the collar 94 back again and free the brake.

109 indicates a collar which is suitably secured to the end of the rock shaft 49 opposite the lever 53 and is provided with an 105 arm 110 preferably integral therewith.

111 indicates a rock shaft which is journaled in suitable bearings 112 on the frame 11.

113 indicates a collar which is keyed or 110 otherwise secured to one end of the rock shaft 111 in registry with the collar 109 and is provided with an arm 114 projecting upward therefrom and preferably integral therewith.

115 indicates a link which is pivotally connected at one end to the end of the arm 110 and at the other end with the end of the arm 114, whereby, when said rock shaft 49 is rocked in either direction, the rock shaft 111 will be correspondingly rocked.

116 indicates a collar which is keyed or otherwise secured to the rock shaft 111 in registry with the spider 22 and is provided upon its periphery with suitable lugs 117—125 118 preferably formed integral therewith. By means of flexible rods 119—120, the ends of the flexible brake band 24 are connected respectively with the lugs 117 and 118. The ends of the rods 119—120 are screw-threaded 130

so that they may be adjustably secured to the lugs 117—118 by means of nuts 121—122.

When the rock shaft 49 is rotated counter-clock-wise by the swinging of the lever 53 from its "off" position into the "slow" position,—that is to say from right to left in Fig. 2,—by means of the engagement of the pawl 56 with the ratchet teeth 51, the rock shaft 111 will be rocked in the opposite direction, tightening the brake band 24 and thereby braking the spider 22 and holding it against rotation. When the pawl 56 is thrown out of engagement with the ratchet teeth 51 by the pin 57 as the lever 53 passes the slow speed position, the spring 69 at once rocks the shaft 49 clock-wise back again to normal position, which, rotating the rock shaft 111 in the opposite direction, frees the brake 25 and permits the spider 22 to rotate. 10 200 indicates a controller which is adapted to be connected by suitable wires to the motor A, and is provided with the usual controller handle 201. The controller may be of any well-known type, and the handle is adapted when swung from the "off" to "slow" position to drive the motor at a slow speed and when moved from the "slow" past the several contact points 202 to gradually turn on more and more current to the 15 motor so as to gradually bring it to its full speed.

203 indicates a link, one end of which is pivotally connected to the controller handle 201 and is provided at its other end with a piston 204 which slides air-tight in a dash-pot 205 provided at its closed end with a small opening 206 to gradually permit the air behind the piston to escape as the piston is moved inward.

40 207 indicates a collar which is journaled on the short shaft 208 supported in suitable bearings from the framework. The collar 207 is provided with two arms 209—210, preferably formed integral with said collar. 45 The collar is notched on its periphery so as to form a shoulder 211 adapted to be engaged by a dog hereinafter described. The upper end of the arm 209 is pivotally connected with the link 203.

50 212 indicates a rod which is pivotally connected at one end to the lower end of the arm 210, and is rigidly connected at the other end with the block 213 which is rigidly secured within one end of a cylinder 214.

215 indicates a piston which is slidably mounted in the cylinder 214.

216 indicates a spiral spring interposed between the block or head 213 and the piston 215 inside of the cylinder 214.

217 indicates a piston rod one end of which is secured to the piston 215 and the other pivotally connected with the lower end of the lever 53.

65 218 indicates a lug which, by means of a

set-screw or other appropriate means, is adjustably secured to the piston-rod 217.

219 indicates a collar which is journaled on a suitable shaft 220, supported in suitable brackets from the framework and provided with two arms 221—222 preferably formed integral with the collar. 70

223 indicates a link one end of which is pivotally mounted upon the arm 221 and the other end passes freely through a block 224 preferably formed integral with and depending from the collar 207. 75

225 indicates a collar which is secured to the link 223.

226 indicates a spring which is interposed between the block 225 and the block 224, and operates by bearing against said block 225 when the collar 224 is held in fixed position to force the lower arm on the collar 219 to the left in Fig. 2. 80

227 indicates a link, one end of which is connected pivotally with the upper end of the arm 222 and the other end is pivotally connected with the lower end of an arm 228 depending from and preferably formed integral with a collar 229 which is journaled upon a suitable shaft 230 mounted in suitable supports in the machine. 90

231 indicates a dog which is secured on the collar 229 and projects to the left over the collar 207 so as to engage the shoulder 211 on said collar 207 and when so engaged to prevent the counter-clockwise rotation of the collar 207. The pressure of the spring 226 on the collar 225 and block 224 tends to force the rod 223 to the left, rocking the arm 221 to the left and the arm 222 to the right, and hence, through the connection of the link 227, to rock the arm 228 to the right and to yieldingly hold the dog 231 in engagement with the surface of the collar 207. 100

The operation of the above-described mechanism is as follows: When the lever 53 is at full speed position, as shown in the figures, the controller handle is also moved to the full speed, the motor is running at full speed, the clutch members are engaged, both brakes are off, and, the arm 61 being thrown by the cam 64 out of engagement 110 with the lug 60, the shaft 49 is yieldingly held in normal position by the spring 69, and the driving mechanism is running at full speed. If the lever 53 is now swung to the right to the "off" position, the

cam 64 will be moved out of the way of the arm 61 which will allow the arm 61 to drop toward the normal position with the latch 63 bearing against the surface of the lug 60 and ready to drop into position behind it 120

when the lug 60 is raised by the rotation of the rock shaft 49 by the movement of the lever in the other direction as hereinafter described. As the lever 53 swings away from the full speed position, by the action 125 130

of the link 72, segmental gear 73, bevel gear 75, rock-shaft 74, and link 71, the slide rod 78 will be moved inward so as to disengage the clutch members by the action of the collar 82 on fork 87 of lever 86. By the same movement of the lever, the pawl 58, before the lever 53 reaches the "off" position, will engage the teeth 52 of the disk 50, rocking the shaft 49 clock-wise. Just before the lever reaches the "off" position, the pawl 92 will by its movement engage the lug 95 on collar 94, rocking it in the same direction, and, applying the brake 43 to the clutch drum 41, will stop the movement of the mechanism and of the press, and the parts will be held in this braked position as long as the lever is held in its "off" position. At the same time, by this motion of the lever to the right, the controller arm will be swung to the right to the "off" position. This will be accomplished by the lower end of the lever 53 pulling the piston-rod 217 to the left, pulling with it the cylinder 214 and the rod 212. This rocks the lower arm 207 on the collar 207 to the left, and, moving the upper arm to the right through the medium of the rod 203 swings the controller arm to the right to the "off" position, the parts being properly adjusted to so move it, and moving the piston 204 out to the open end of the cylinder 205. This same movement will free the lug 218 from engagement with the arm 221 leaving it free to rock under the influence of the spring 226. As the collar 207 rocks in a clock-wise direction, the pawl or dog 231 drops into the notch beyond the shoulder 211 and the full movement to the right is such as to carry the shoulder 211 somewhat beyond the engaging end of the dog 231 so as to permit it to be moved to the left on the return movement of the lever 53 hereinafter described a sufficient amount to bring the controller arm 201 upon the slow speed before the dog engages the shoulder. The machine is now in position to be started.

The lever 53 is now swung to the left, moving of course its lower end to the right. This pushes the piston rod 217 to the right, against the spring 216 in the cylinder 214, and, the parts being free to move by reason of the fact that the dog 231 is somewhat beyond the shoulder 211 as above described, and the tension of the spring being sufficient to permit of it, the upper arm 209 is moved to the left, swinging the controller arm 201 from the "off" to the "slow" position, and moving the piston 204 slightly inward into the dash-pot 205. This rocking of the collar 207 slightly to the left or counter-clockwise brings the shoulder 211 into engagement with the dog or pawl 231, the parts which operate the controller being thus held against further movement until released as hereinafter described. The lever

is thus brought into "slow" position, and the motor is set running at slow speed. As soon as the lever 53 begins its movement to the left, the pawl 56 immediately engages one of the teeth 51 on the ratchet 50, moving it contra-clock-wise in the figures, and rocking with it in the same direction the shaft 49 against the action of the spring 69. This movement first of all releases the pawl 92 from the lug 95, leaving the sleeve 94 free to be rocked by the spring 100 which immediately acts to rock the sleeve 94 and free the stopping brake 43 from the mechanism. The same movement of the lever begins to move the slide rod 78, but the parts are so spaced that the collar 84 does not immediately bear upon the fork 87 to throw the clutch members into engagement until after the slow speed position is passed. The rocking of the rock shaft 49, however, immediately begins to tighten the flexible brake band 24 and thus applies the brake 25 to the spider 22, holding the same against rotation. At the same time the lug 60 is lifted to a position permitting the arm 61 to move to its lowest position with the latch 63 dropping below the lug 60 and preventing the return of the rock shaft 49 by the operation of the spring 69 to its normal position until after the arm 61 is swung out again by the action of the cam on the further movement of the lever. When the lever 53 is thus held at the slow speed position, the pawl 56 is still in engagement with the teeth 51, but the lever has moved into such position that the lug 57 is just ready to act upon the arm 56^a of the pawl 56 so as to move it out of engagement with the ratchet teeth 51 upon the further movement of the lever 53. The stopping brake 43 being thus off, and the spider 22 being held against rotation by the brake 25, the mechanism and the press will be driven at the slow speed in the manner hereinabove described, and will continue to so run until the further movement of the lever. So far, the motor is running at slow speed, and the slow-speed driving mechanism only is engaged.

It now being desired to pass to the high speed, the lever is swung still farther to the left toward the position shown in the figures. The pin 57, as soon as the lever is swung out of slow-speed position, engaging the arm 56^a of the pawl 56, throws it out of engagement with the teeth 51, thus preventing further contra-clock-wise rocking of the rock shaft 49, which, however, is prevented by the engagement of the latch 63 with the lug 60 from itself being returned by the spring 69 to its normal position which would otherwise free the brake 25 from the spider 22. By this further movement of the lever, the spring-seated collar 84 coming into contact with the fork 87, rocks the lever 86 and throws the clutch members into engagement, 130

causing the clutch drum 41 to gradually take the full speed of the driving shaft 19 and thus driving the press by the full speed driving mechanism. As this full speed movement is taken up, and the mechanism is running by the engagement of the clutch members, and just as a complete and tight engagement of the clutch members is being made, the cam 64 on the lower end of the lever 53 engaging the lower end of the arm 61, pushes it to one side, freeing the latch 63 from the lug 60. This permits the spring 69 to at once rock the shaft into normal position, freeing the brake 25 from the spider 22 and permitting it to take up the movement of the shaft 19. At the same time that the movement of the lever from slow to full speed is causing the operation of the variable speed driving mechanism above described, the movement of the lower arm of the lever 53 to the right is moving the piston-rod 217 to the right, carrying with it the lug 218. This of course would cause a movement of the arm 210 to the right if it were not for the engagement of the pawl 231 with the shoulder 211, which prevents the counter-clockwise rotation of the collar 207. The effect of the movement, therefore, until the shoulder is released from the dog as hereinafter described, is simply to compress the spring 216 in the cylinder 214, and the motor therefore during the period of bringing the full speed driving mechanism into engagement is running at slow speed. The parts, however, are so adjusted that just before the lever reaches the extreme limit of its motion to the full-speed position the dog 218 is brought into contact with the arm 221 on the collar 219, rocking it to the right against the action of the spring 226. This of course rocks the arm 222 to the left, and, through the medium of the link 227 and arm 228, the pawl or dog 231 is lifted out of engagement with the shoulder 211, leaving the collar 207 free to rotate. The expansive force, therefore, of the spring in the cylinder 214, compressed as above described, thereupon forces the cylinder 214 to the right in Fig. 2, moving with it the link 212 and the arm 210, thus moving the arm 209 to the left, forcing the piston 204 into the dash-pot 205, and thereby swinging the controller arm from the slow speed position over the various contacts to the full speed position. The spring in the cylinder 214, however, does not act instantly, because the piston 204 in the dash-pot 205 compresses the air between it and the end of the cylinder, the air escaping only through the small opening 206. This will of course prevent the instant acting of the spring and therefore will cause the gradual motion of the controller arm from slow speed to high speed, passing over the several contacts, and thus, the high speed driving mechanism, being already engaged

as above described, will cause the gradual speeding of the motor from slow to high speed.

It will thus be seen that by a single movement of the lever from left to right the 70 motor is first set in slow speed motion and the parts operating the controller are locked so as to prevent the controller arm moving to throw the motor into full speed until subsequently released. As soon as the motor is 75 running at slow speed, the stopping brake is thrown off, the slow speed mechanism is thrown into operative relation with the press, and, as the movement of the lever continues, the driving mechanism is moved 80 into full speed relation before the slow speed driving mechanism is thrown out of operative relation. This, as has been pointed out, prevents the occurrence of a period of time between the throwing out of the 85 slow speed and the throwing in of the high speed during which the press, running by its own momentum only, would slow down enough to cause breakages in the web when the high speed was thrown in. It will also 90 be seen that the motor continues to run at the slow speed substantially until the high speed driving mechanism is thrown into operative relation and that as soon as that high speed engagement of the driving mechanism 95 is effected the same movement of the lever has caused such movement of the parts that the devices which held the controller at the slow speed position hitherto have been released and the controller arm is gradually 100 moved so as to gradually increase the speed of the motor from slow speed to high speed. I therefore provide, by the above devices, a mechanism by which the relative proportion of the slow speed to the high speed of the 105 press may be considerably increased by means of which the high speed is not taken up at once, but, after the driving mechanism has been moved into high speed position, the speed of the motor or other prime mover 110 is also gradually and automatically increased so as to gradually increase the speed of the high speed mechanism until it reaches full speed.

What I claim as my invention and desire 115 to secure by Letters Patent is,—

1. In combination, a prime mover, a controller therefor, a driving shaft driven by said prime mover, a driving gear, slow speed mechanism connected with said driving shaft and adapted to be connected with said driving gear, high speed mechanism connected with said driving shaft and adapted to be connected with said driving gear, shifting mechanism connected with said controller and with said slow speed and said high speed mechanisms and adapted by its movement to shift said controller to slow speed position, to operatively connect said slow speed mechanism with said driving 120
- 125
- 130

gear, and then to operatively connect said high speed mechanism with said driving gear, and then to shift said controller to high speed position.

5 2. In combination, a prime mover, a controller therefor, a driving shaft driven by said prime mover, a driving gear, slow speed mechanism connected with said driving shaft and adapted to be connected with said driving gear, high speed mechanism connected with said driving shaft and adapted to be connected with said driving gear, and then to gradually shift said controller to high speed position.

10 10 15 20 25 30 35 40 45 50 55 60 65 70 75 80 85 90 95 100 105 110 115 120 125 130

2. In combination, a prime mover, a controller therefor, a driving shaft driven by said prime mover, a driving gear, slow speed mechanism connected with said driving shaft and adapted to be connected with said driving gear, high speed mechanism connected with said driving shaft and adapted to be connected with said driving gear, shifting mechanism connected with said controller and with said slow speed and said high speed mechanisms and adapted by its movement to shift said controller to slow speed position, to operatively connect said slow speed mechanism with said driving gear, then to operatively connect said high speed mechanism with said driving gear, and then to gradually shift said controller to high speed position.

3. In combination, a prime mover, a controller therefor, a driving shaft driven by said prime mover, a driving gear, slow speed mechanism connected with said driving shaft and adapted to be connected with said driving gear, high speed mechanism connected with said driving shaft and adapted to be connected with said driving gear, shifting mechanism connected with said controller and with said slow speed and said high speed mechanisms and adapted by its movement to shift said controller to slow speed position, to operatively connect said slow speed mechanism with said driving gear, then to operatively connect said high speed mechanism with said driving gear while said slow speed mechanism is still in operative relation with said driving gear, and then to disconnect said slow speed mechanism from said driving gear and shift said controller gradually to high speed position.

4. In combination, a motor, a controller therefor, a driving shaft driven by said motor, a driving gear, slow speed mechanism connected with said driving shaft and adapted to be connected with said driving gear, high speed mechanism connected with said driving shaft and adapted to be connected with said driving gear, a lever, mechanism operated by said lever and connected with said controller and with said low speed and high speed mechanisms and adapted by the movement of said lever to shift said controller to slow speed position, to operatively connect said slow speed mechanism with said driving gear, then to operatively connect said high speed mechanism with said driving gear, and then to shift said controller to high speed position.

5. In combination, a motor, a controller therefor, a drive shaft, a driving gear, slow speed mechanism connected with said driving shaft and adapted to be operatively connected with said driving gear, high speed mechanism connected with said driving gear, and then to release said slow speed mechanism, connections between said lever and said controller and adapted by the movement of said lever to shift said controller to slow speed position, said connections including a spring adapted to be compressed by the movement of said lever and by its resiliency to move said controller from slow speed to high speed position.

mechanism connected with said driving shaft and adapted to be operatively connected with said driving gear, a lever, mechanism connected with said lever and with said slow speed and said high speed mechanisms and adapted by the movement of said lever to operatively connect said slow speed mechanism with said driving gear, then to operatively connect said high speed mechanism with said driving gear, and then to release said slow speed mechanism, connections between said lever and said controller and adapted by the movement of said lever to shift said controller to slow speed position, said connections including a spring adapted to be compressed by the movement of said lever and by its resiliency to move said controller from slow speed to high speed position.

6. In combination, a motor, a controller therefor, a drive shaft, a driving gear, slow speed mechanism connected with said driving shaft and adapted to be operatively connected with said driving gear, high speed mechanism connected with said driving shaft and adapted to be operatively connected with said driving gear, a lever, mechanism connected with said lever and with said slow speed and said high speed mechanisms and adapted by the movement of said lever to operatively connect said slow speed mechanism with said driving gear, then to operatively connect said high speed mechanism with said driving gear, and then to release said slow speed mechanism, connections between said lever and said controller and adapted by the movement of said lever to shift said controller to slow speed position, said connections including a spring adapted to be compressed by the movement of said lever and by its resiliency to move said controller from slow speed to high speed position.

7. In combination, a motor, a controller therefor, a drive shaft, a driving gear, slow speed mechanism connected with said driving shaft and adapted to be operatively connected with said driving gear, high speed mechanism connected with said driving shaft and adapted to be operatively connected with said driving gear, a lever, mechanism connected with said lever and with said slow speed and said high speed mechanisms and adapted by the movement of said lever to operatively connect said slow speed mechanism with said driving gear, then to operatively connect said high speed mechanism with said driving gear, and then to release said slow speed mechanism, connections between said lever and said controller and adapted by the movement of said lever to shift gradually from slow speed to high speed position.

- movement of said lever to shift said controller to slow speed position, means adapted to automatically lock said controller in slow speed position and to be released by the further movement of said lever, said connections including a spring interposed between said lever and said controller and adapted to be compressed by the further movement of said lever and by its resiliency 5 to move said controller from said slow speed position to high speed position, and also including means connected with said controller and adapted to act against said spring to cause said controller to shift gradually 10 from slow speed to high speed position.
8. In combination, a motor, a controller therefor, a drive shaft, a driving gear, slow speed mechanism connected with said driving shaft and adapted to be operatively connected with said driving gear, high speed mechanism connected with said driving shaft and adapted to be operatively connected with said driving gear, a lever, mechanism 15 connected with said lever and with said slow speed and said high speed mechanisms and adapted by the movement of said lever to operatively connect said slow speed mechanism with said driving gear, then to operatively connect said high speed mechanism with said driving gear, and then to release said slow speed mechanism, connections between said lever and said controller and adapted by the movement of 20 said lever to shift said controller to slow speed position, means adapted to automatically lock said controller in slow speed position and to be released by the further movement of said lever, said connections including a spring interposed between said lever and said controller and adapted to be compressed by the further movement of said lever and by its resiliency to move said controller from said slow speed position to 25 high speed position, and also including a dash-pot, a piston therein, and connections between said piston and said controller and adapted to force said piston into said dash-pot when said controller is shifted from slow speed to high speed position and thereby act against said spring.
9. In combination, a prime mover, a controller therefor, a main drive wheel having a clutch member, a co-acting clutch member driven by said prime mover, speed-reducing gearing connected with said main drive wheel for driving the same from said prime mover at a slower speed, means for connecting said speed-reducing mechanism with said prime mover and arranged to be automatically disconnected from said prime mover when said clutch members co-operate to increase the speed of said main drive wheel, a lever for throwing said speed-reducing mechanism and said clutch members

into and out of operative engagement with said main drive wheel, and connections between said lever and said controller and adapted to move said controller to slow speed position before said speed-reducing mechanism is put into operative relation with said driving wheel, and, after said clutch members are brought into engagement, to move said controller from said slow speed to high speed position.

10. In combination, a motor, a controller therefor, a driving shaft driven by said motor, a main drive wheel having a clutch member, a co-acting clutch member driven by said driving shaft, speed-reducing gearing connected with said main drive wheel for driving the same from said main driving shaft at a slower speed, ratchet mechanism for connecting said speed-reducing mechanism with said driving shaft and arranged to be automatically disconnected from the driving shaft when said clutch members co-operate to increase the speed of the main drive wheel, and shifting mechanism connected with said speed-reducing gearing, with said clutch members, and with said controller, and adapted by its movement to first shift said controller to slow speed position, then to bring said speed-reducing gearing into operative relation with said driving wheel, then to bring said clutch members into co-operative relation with each other, and then to shift said controller from slow speed to high speed position.

11. In combination, a motor, a controller therefor, a driving shaft driven by said motor, a main drive wheel having a clutch member, a co-acting clutch member driven by said driving shaft, speed-reducing gearing connected with said main drive wheel for driving the same from said main driving shaft at a slower speed, ratchet mechanism for connecting said speed-reducing mechanism with said driving shaft and arranged to be automatically disconnected from the driving shaft when said clutch members co-operate to increase the speed of the main drive wheel, a lever, connections between said lever and said speed-reducing gearing and said clutch members and adapted to throw the same into and out of operative relation with said main drive wheel, connections between said lever and said controller and adapted by the movement of said lever to move said controller to slow speed position before said speed-reducing gearing is brought into operative relation with the drive wheel, and said connections including between said lever and said controller adapted to be compressed by the movement of said lever in bringing said clutch members into co-operative relation and by its resiliency to move said controller from slow speed to high speed position.

12. In combination, a motor, a controller

therefor, a driving shaft driven by said motor, a main drive wheel having a clutch member, a co-acting clutch member driven by said driving shaft, speed-reducing gearing connected with said main drive wheel for driving the same from said main driving shaft at a slower speed, ratchet mechanism for connecting said speed-reducing mechanism with said driving shaft and arranged to 5 be automatically disconnected from the driving shaft when said clutch members coöperate to increase the speed of the main drive wheel, a lever, connections between said lever and said speed-reducing gearing and said 10 15 clutch members and adapted to throw the same into and out of operative relation with said main drive wheel, connections between said lever and said controller and adapted by the movement of said lever to move said

controller to slow speed position before said speed-reducing gearing is brought into operative relation with the drive wheel, said connections including between said lever and said controller adapted to be compressed by the movement of said lever in bringing said clutch members into coöperative relation and by its resiliency to move said controller from slow speed to high speed position, and also including means connected with said controller and adapted to act against said 25 30 spring to cause a gradual movement of said controller from slow speed position to high speed position.
